US0D1076425S

(12) **United States Design Patent** (10) **Patent No.:** **US D1,076,425 S**
(45) **Date of Patent:** **** May 27, 2025**

(54) **WALLET ATTACHMENT**

(71) Applicant: **ANNEX PRODUCTS PTY. LTD.**,
South Yarra (AU)

(72) Inventors: **Elliot Staley**, South Yarra (AU); **Leigh Ryan**, South Yarra (AU)

(73) Assignee: **ANNEX PRODUCTS PTY. LTD.**,
South Yarra (AU)

(**) Term: **15 Years**

(21) Appl. No.: **29/887,061**

(22) Filed: **Mar. 16, 2023**

(51) LOC (15) Cl. **03-01**

(52) U.S. Cl.

USPC **D3/249**; D3/247

(58) **Field of Classification Search**

USPC D3/247, 248, 249, 250, 251, 252, 253,

(57) **CLAIM**

The ornamental design for a wallet attachment as shown and described.

DESCRIPTION

FIG. 1 is a rear perspective view of a wallet attachment in accordance with our new design;

FIG. 2 is a front elevation view of the wallet attachment of FIG. 1;

FIG. 3 is a rear elevation view of the wallet attachment of FIG. 1;

FIG. 4 is a right side elevation view of the wallet attachment of FIG. 1;

FIG. 5 is a left side elevation view of the wallet attachment of FIG. 1;

FIG. 6 is a top plan view of the wallet attachment of FIG. 1; and,

FIG. 7 is a bottom plan view of the wallet attachment of FIG. 1.

The broken lines depict portions of the wallet attachment that form no part of the claimed design.

1 Claim, 5 Drawing Sheets
